MAGAZINE STRIPPING MACHINE

Clifton A. Cobb, University City, Mo.

Application September 7, 1948, Serial No. 47,970

6 Claims. (Cl. 164—47)

1

This invention relates to a machine for removing from a magazine or other soft cover publication, an identifying portion of its cover, and for rendering the publication further unsaleable.

The customary business arrangement for the distribution of most periodicals, generally called magazines, is such that distributors thereof receive these publications on consignment and return for credit unsold copies. In order to avoid considerable shipping costs, it is common practice to return only an identifying portion of the front cover as evidence of unsold copies. Additionally, it is also customarily required that the publication be further destroyed so as to render it definitely unsaleable.

It is the object of this invention to provide a novel machine, which I have descriptively named a magazine stripping machine, having means for detaching an identifying portion of a magazine cover, for picking up, counting, and stacking these detached portions or tabs, and for further destroying the magazine so as to render it definitely unsaleable.

Another object is to provide a machine of this character in which the manual effort of an operator is reduced to feeding magazines to the machine and tripping a single operating lever.

Another object is to provide a machine of this kind having cutting blades operable to detach a portion of a magazine cover when it is fed into position, and having vacuum operated pick-up means for removing and stacking the detached portions or tabs.

A further object is to provide in a machine of this kind, the combination of a rotary slitting blade and a reciprocating chopping blade arranged perpendicular thereto and spaced horizontally therefrom, and guide means, whereby a magazine may be guided longitudinally of the slitting blade, thereby to slit its cover along its bound edge, to a position in which the chopping blade acts to cut transversely through the magazine to complete the detachment of a portion of the cover and to further destroy the magazine.

These and other objects and advantages will become apparent from the following complete description of a preferred form of the invention when read in connection with the accompanying drawings.

In the drawings:

Fig. 1 is a side elevation of a machine constructed in accordance with the present invention;

2

Fig. 2 is a front elevation of the machine shown in Fig. 1;

Fig. 3 is a plan view of the machine shown in Figs. 1 and 2;

Fig. 4 is an enlarged detail view of the upper left corner of the view in Fig. 1 with parts broken away to more clearly illustrate;

Fig. 5 is an enlarged sectional view taken on line 5—5 of Fig. 1;

Fig. 6 is an enlarged sectional view of the manually operated tripping switch taken on line 6—6 of Fig. 3;

Fig. 7 is a diagram of the electrical control circuits;

Fig. 8 is an enlarged view of the circular slitting blade 45 and the adjacent cut limiting disc 58.

Referring to the drawings more particularly, a frame is indicated for the machine having vertical legs or members 10, lower horizontal members 11, and upper horizontal members 12. The members 10, 11 and 12 may be steel angles suitably connected as by welding or riveting. A top counter or platen 13 is provided, and is attached to the upper horizontal frame members 12 by any suitable means. The platen 13 may be constructed of wood, fibre board, or metal. There is an electric motor 14, suitably mounted on vertical supports 15, which are in turn supported by and connected to a horizontal support channel 16, carried by the lower horizontal frame members. Mounted to the right of and below the motor 14 (Fig. 1), on a pair of horizontal support members 17, is a vacuum pumping device 18, driven by the motor 14, through a belt 19. Mounted between the front and rear lower horizontal frame members 11 and supported thereby is a vacuum tank 20, having a connection 21, with the vacuum pump.

A reciprocating shear assembly mounted above the platen 13 and at the rear of the machine is generally indicated at 22. The shear assembly is supported on a horizontal member 23 which is attached at its ends to the upper horizontal members 12, as by angle clips 24. The member 23 is cut-out as indicated at 25 in Fig. 4, and throughout the length of this cut-out portion it is provided with a hardened steel insert 26. This cut-out portion of the support member 23 with the hardened insert forms the lower stationary blade of the shear. The platen 13 is also cut-out to the line 25 as indicated in the plan view, Fig. 3. A movable shear blade 27, is mounted on a horizontal movable

shear bar 28, which is likewise cut-out to the

line 25. The shear bar 28 is provided with four vertically elongated bosses 29 which together with the bar, have a vertical bore extending therethrough adapted to slidably fit four round vertical support standards 30.

The supports 30 are rigidly attached at their lower ends to the support bar 23 as by welding, and at their upper ends support an upper horizontal support bar 31. Mounted on the upper horizontal bar 31 is a pair of spaced pedestal bearings 32, in which is journalled an eccentric shaft 33. Mounted on the shaft 33 and rigidly attached thereto for rotation therewith is a pair of eccentrics 34, having surrounding collars or followers 35. A pair of connecting rods 36, rigidly attached to the shear bar at their lower ends and pivotally connected to the eccentric collars 35 at their upper ends by pivot pins 37, transmit vertical motion from the eccentrics to the shear bar 28 upon rotation of the shaft 33. The rods 36 are guided in the upper horizontal support bar 31.

Journalled on the left end of the shaft 33 is a fly wheel 38. The fly wheel is driven by the motor 14 through a V-belt 39. A single revolution of the fly wheel is intermittently transmitted to the eccentric shaft through a single trip type clutch mechanism generally indicated at 40. This clutch mechanism is of the type and construction commonly employed in punch presses, and its operation is well known and understood. The clutch mechanism includes a trip arm 41 which when moved upward slightly, causes the mechanism to be tripped, thereby locking the fly wheel to the eccentric shaft for their rotation together for one revolution only after which a locking dog is thrown out and the fly wheel permitted to again run free. A pressure plate 42, for holding the magazine in position under the shear is provided, and suspended from the shear bar 28 by bolts 43. The plate is provided with springs 44, which are biased between the bar 28 and the plate. The plate 42 may be formed upward on its front edge at a suitable angle as indicated to include and feed in dog-eared covers.

Mounted just above the platen and slightly forward of, and near the left end of the reciprocating shear is a circular rotary slitting blade 45. The blade 45 is mounted on one end of a shaft 46, for rotation therewith. The shaft 46 is journalled in a vertically adjustable bearing 47. The bearing 47 is connected by means of a rod 48, to one end of a lever 49. The lever 49 is pivoted at its center on a pivot 50, which is carried by a bracket 51. The other end of the lever 49 is perforated to receive the lower end of an adjusting screw 52. A nut 53 welded to the end of lever 49 threadedly receives the adjustment screw 52. The upper end of the adjustment screw 51 passes through and threadedly engages an internally threaded sleeve 54, which is attached near its upper end, by means of a flange and screws as indicated, to the upper surface of the platen 13. The screw 52 is provided with a handle 55, at its upper end. A spring 56 biased between the lower end of the sleeve 54 and the end of lever 49 provides friction thereby to retain the lever and therefore the rotary slitting blade in a vertically adjusted position.

The other end of the shaft 46 carries a pulley 57, keyed thereto. The pulley 57 bears against the V-belt 39 and is driven thereby. Mounted on the shaft 46 alongside the rotary cutting blade 45 is a circular guard disc or depth of cut gauge 58, just slightly smaller in diameter than the cut-

ting blade for limiting the depth of cut by the blade 45. The disc 58 also serves as a guard against serious injury. There is a conventional type counter 59, mounted above the eccentric shaft 33, and supported on a bridge like bracket 60. The counter is provided with an arm 61, and an arm 62, attached to the eccentric shaft 33, for rotation therewith engages the counter arm at each revolution of the eccentric shaft to register one unit upon the counter.

Mounted at the rear of the machine and at the left side thereof is a vacuum operated pick-up device comprising an inverted cup element 63, carried on the outer free end of a horizontally swinging arm 64. The horizontally swinging arm 64 is attached to the upper end of a rotatable vertical rod 65 for rotation therewith. The vertical rod 65 rotates in a sleeve 66, which is rigidly attached to the frame as by an integral lug 67, and screws 68. The rod 65 is provided with an upper thrust collar 69 which bears against the upper end of the sleeve. The arm 64 is also arranged to swing vertically and is therefore pivotally connected by a horizontal pivot 70, to a bracket 71, which in turn is riveted to the upper end of the rod 65. Mounted on the upper end of the sleeve 66 is a circular cap member 72, having a cam surface 73, which is engaged by a follower pin 74, on the swinging arm 64. The arrangement is such that as the outer end of the arm 64 swings clockwise horizontally with the rod 65, it will also swing vertically downward due to its own weight on pivot 70 as the pin 74 follows the cam surface 73.

There is a conduit 75 connecting the pick-up cup 63 with the vacuum tank 20. Interposed in this conduit is an electromagnetically operated control valve 76, having an electromagnet 76a. The valve 76 is normally closed by gravity or spring pressure and is opened by the electromagnet upon its energization. There is also a flexible section 77, interposed in conduit 75 which is sufficiently resilient to permit the free movement of the arm 64 and the cup 63 to which one end of the conduit is attached. A removable collecting box 78, for accumulation of the detached tabs is provided and supported at the rear and left side of the machine on a bracket 79, as indicated. Rigidly attached to the lower end of the rod 65 for rotation therewith is an arm 80, adapted to engage and actuate a switching device 81, mounted on the frame and which controls the energization of electromagnet 76a. The arrangement is such that as the cup 63 and arm 64 swing clockwise toward the shear, the switch arm 80 moves away from the switch 81, permitting it to move to a normally closed position in which an energizing circuit for the electromagnet 76a is completed, thereby to open valve 76 and establish communication between the pick-up cup 63 and vacuum tank 20. As the cup and arm swing counterclockwise back to a position over the collecting box 78, the arm 80 again contacts the switch 81, breaking the circuit, thereby causing the valve 76 to close and cut off suction to the cup 63. The cup 63 is provided with a small constant bleeder hole at 83 to permit pressure to rapidly rise between the cup and valve 76 when the same closes.

Supported under the platen 13 and approximately centrally of the machine is a vacuum operated actuator 84, having a diaphragm chamber and a movable wall or diaphragm and having an actuating rod 85, attached to the diaphragm and extending therefrom. A conduit 85a con-

necting the diaphragm chamber with the vacuum tank 20 is provided. Interposed in the conduit 85a is an electromagnetically operated valve having a valve chamber 87, and an electromagnet 88. The valve chamber is provided with an inlet 89, an outlet 90, and a bleeder 91. The valve chamber includes a double end valve operated by the electromagnet and adapted to be moved by the electromagnet when energized to a position in which communication between the diaphragm chamber and the vacuum tank is established and in which the bleeder 91 is closed. The valve is also arranged to move by gravity or spring pressure upon deenergization of the electromagnet to a position in which communication between the diaphragm chamber and the vacuum tank is cut off and in which the vent 91 is opened.

The actuating rod 85 is pivotally connected at its outer end to an arm 92, rigidly attached to for rotation with the rod 65 of the pick-up mechanism. Pivotally connected to the actuating rod toward its outer end is a second rod 93, which transmits motion to the trip rod 41 thru a bell crank device 94. A lost motion slot 95, is provided at the connection between rods 85 and 93 for a purpose to be explained hereinafter. A spring 96, biased between the actuator 84 and a transverse pin 97 in the rod 85, returns the mechanism toward the left (Fig. 1), when suction is cut off and the diaphragm chamber is bled.

A movable control switch 98, for controlling the electromagnet 88 is provided and mounted on the platen 13. The switch 98 is provided with an extended actuating arm 99, which extends transversely over a guide rail 100, also mounted on platen 13. The switch 98 is slidably mounted in an elongated case 101, which is fastened to the surface of the platen and which is provided with elongated slots in the top and bottom thereof. There is a pair of flat springs 102, attached to the top of switch 98 which bear against the underside of the top of case 101, thereby to frictionally hold the switch in an adjusted position. A spring 102a urges the arm 99, and the switch 98 to a switch open position. A manually operated master control switch 103, is provided for control of the motor 14 and the electromagnets 76a and 88.

A circuit for the energization of the motor 14 and electromagnetic actuators 76 and 88 is provided (see Fig. 7). The circuit includes the leads 104 and 105 to the motor 14. These leads are connected to a suitable source of power. Connected across the leads 104 and 105 is a circuit for the energization and control of the electromagnetic actuator 76a, which comprises the leads 106, 107, the control switch 81 and the lead 108. Also connected across the leads 104 and 105 is a circuit for the energization and control of the electromagnetic actuator 88 which comprises the leads 109, 110, the control switch 98 and the lead 111. The master control switch 103 is interposed in series with the motor and the above mentioned electromagnetic circuits as indicated.

Operation

In operation the master switch 103 is closed to start the motor 14, which operates the vacuum pumping device to exhaust the tank 20 and rotates the fly wheel 36. A publication to be processed is placed on the front of the platen 13 with its bound edge lying against the guide rail 100 and with its top toward the shear. The control switch 98 has been slidably positioned in the case 101 for this particular length magazine so that the

control arm 99 will be contacted to close the somewhat sensitive switch 98 by the hand of the operator in its natural position on the magazine being fed when the top or forward edge of the magazine has been moved rearward beyond the reciprocating shear a predetermined amount. As the magazine is moved rearward along the guide rail 100 and before the control arm is contacted, its cover will be slit parallel with and adjacent to its bound edge by the rotary blade 45. The depth of the cut by the slitting blade is not critical so long as the cover has been completely severed on that line. Usually several pages below the cover will also be cut. The guard disc 58 however gauges the depth of cut sufficiently close to prevent unnecessary wear of the blade. The adjusting screw 52 is turned to raise and lower the blade and guard disc to accommodate the thickness of various publications.

When the arm 99 is contacted to close the switch 98, the electromagnet 88 is energized, moving its valve to an open position in which the bleeder 91 is closed and in which communication between the diaphragm chamber and the vacuum tank is established. This action causes the diaphragm to move the actuating rods 85 and 93 toward the front of the machine or toward the right in Fig. 1. Rod 85 will therefore, due to its connection with the arm 92 and rod 65, cause this rod to rotate clockwise and the arm 64 carrying the cup 63 to swing toward the shear. As the cup is swung toward the shear, it will also move downward due to the cam surface 73 and will rest upon the top of the magazine portion extending rearward of the shear blade 27. Also as the cup swings toward the shear blade with the rotation of rod 65, the switch contact arm 89 will move away from the switch 81 permitting it to close a circuit for opening the valve 76, whereby suction is communicated to the cup.

During the initial movement of the rod 85, the rod 93 remains motionless until the lost motion 95 is taken up. Further movement of the rod 85 thereafter causes trip rod 41 to be moved upward to trip the clutch mechanism 40 and cause the shear blade to be actuated one stroke. The magazine is thereby cut transversely through and the top cover tab is detached. The purpose of the lost motion 95 is to permit the cup 93 to move into position and to contact and hold the top cover portion before the shear cuts through the magazine. The operator's hand is immediately withdrawn from contact with the control switch lever 99 as he moves to present another magazine. The switch 98 thereupon returns to an open position and the electromagnet is deenergized. When this occurs, its valve returns by gravity or spring pressure to a position in which communication between the diaphragm and the vacuum tank is cut off and the bleeder 91 is opened, thereby to permit the rapid return of the actuating rod 85 under pressure of spring 96.

The return of the actuating rod 85 causes the cup 63 to be swung counterclockwise and upward to a position over the collector box 78 and the switch actuating arm 80 to contact the switch 81 thus breaking the circuit for the electromagnet 76a and cutting off suction to the cup 63. The bleed hole 83 causes a rapid rise in pressure and the detached tab is dropped into the collector box. At the same time, the rod 93 is returning the trip arm and clutch mechanism to a cocked position. The counting device 59 registers one unit each time the shear falls and therefor each time a tab is picked up and deposited in the collector box.

The foregoing description is intended to be illustrative, not limiting, the scope of the invention being set forth in the appended claims.

I claim:

1. In a magazine stripping machine in combination, a platen, means for cutting a rectangular portion from the cover of a magazine placed on said platen comprising a pair of vertical cutting blades supported above said platen and arranged perpendicular to each other, means for actuating said cutting blades, and a vacuum pick-up device for removing the detached cover portions comprising a cup-like element supported above said platen, a source of suction, conduit means connecting said cup element with said source of suction, a control valve in said conduit, a vacuum operated actuator and mechanism actuated thereby for moving said cup element parallel with said platen from a remote position to a position above the detached magazine cover portion and then vertically downward into contact therewith, and for returning said cup element upward and horizontally to said remote position, means having an interconnection with said pick-up mechanism for causing the actuation of at least one of said cutting blades as said mechanism moves said cup element toward a pick-up position, and means operatively connected with said pick-up mechanism for causing said control valve to open as said cup element is moved toward a pick-up position, and to close as said pick-up mechanism returns said cup to said remote position.

2. In a magazine stripping machine in combination, a platen, having a forward and a rear edge, a guide rail on said platen extending rearward from said forward edge, a vertical rotary slitting blade mounted above said platen intermediate of its front and rear edges and parallel with and adjacent said guide rail, said slitting blade having its lower edge spaced a predetermined amount above said platen so that when a magazine is placed on said platen and moved rearwardly under said rotary blade, it will be slit for a depth at least sufficient to sever its cover, a vertically reciprocating chopping blade arranged perpendicular to said slitting blade and spaced rearwardly therefrom, said reciprocating blade being arranged to travel downward sufficiently to completely cut through a magazine on said platen, and a device for controlling the operation of said reciprocating blade including an actuating arm extending transversely of said guide rail and arranged to be contacted by the hand of an operator when feeding a magazine toward said cutting blades.

3. In a machine of the kind described, a table having a forward and rear edge, a guide member on said table extending rearwardly from said forward edge, a first continuously moving cutting blade perpendicular to said table and parallel with said guide member for cutting a magazine parallel to its direction of travel as it is moved rearwardly along said guide member, a second vertically reciprocating cutting blade supported above said table and spaced rearwardly from said first cutting blade and arranged perpendicular thereto for cutting the magazine transversely to its direction of travel as it is moved thereunder, means for driving said first and second cutting blades, said second cutting blade being normally disconnected from said driving means, mechanism for completing a driving connection between said driving means and said second cutting blade when actuated, an actuator for said mechanism, and a control device for said actuator mounted on said

table adjacent said guide member and having an operating lever extending transversely of said guide member and in the path of the hand of an operator when feeding a magazine rearwardly along said guide member so as to be contacted thereby, said control device being adjustable longitudinally of said guide member.

4. In a machine of the kind described, means for cutting a magazine or the like along two perpendicular intersecting lines thereby to detach a rectangular portion of the top sheet or cover therefrom, said cutting means including a reciprocating blade, driving means for the actuation of said cutting means, a vacuum pumping device driven by said driving means for supplying a source of vacuum, a collector box remote from said cutting means for accumulating the detached cover portions, a vacuum pick-up device for picking up the detached cover portions and for depositing them in said collector box including a suction cup element in communication with said source of vacuum, a vacuum operated actuator having communication with said source of vacuum for moving said cup element from a position over said collector box to a position in which it is in contact with the magazine cover portion to be detached and for returning it to its position over said collector box, control means rendered operative to cut off communication between said cup element and said source of vacuum as said cup element is moved to its position over said collector box and to reopen such communication as said cup element is moved toward said cutting means, a counting device having an actuating lever, and means movable with said reciprocating blade for engaging said actuating lever once each stroke thereby to register one unit.

5. In a machine of the kind described, a platen, means for cutting a magazine or the like when placed on said platen along two perpendicular intersecting lines thereby to detach a rectangular portion of the top sheet or cover therefrom, said cutting means being constructed and arranged to cut through the magazine along at least one of said lines, driving means for the actuation of said cutting means, a vacuum pumping device driven by said driving means for providing a source of vacuum, a collector box remote from said cutting means, a vacuum pick-up device for picking up the detached cover portions and for depositing them in said collector box including a suction cup element in communication with said source of vacuum, a vacuum operated actuator for moving said cup element from a position over said collector box to a position in which it is in contact with the surface of the magazine cover portion to be detached and for returning it to its position over said collector box, and control means rendered operative to cut off communication between said cup element and said source of vacuum as said cup element is moved to its position over said collector box and to reopen such communication as said cup element is moved toward said cutting means.

6. In a magazine stripping machine for detaching removing and counting rectangular portions of one cover of a magazine, the combination of a circular rotary slitting blade, a reciprocating chopping blade arranged perpendicular to said slitting blade, a vacuum pick-up device, a counting device, means for driving said cutting blades, said reciprocating chopping blade being normally disconnected from said driving means, a clutch mechanism for completing a driving connection between said driving means and said chopping

blade, an actuator for simultaneously effecting the operation of said clutch mechanism and said vacuum pick-up device, and manually operated control means for controlling the operation of said actuator.
